E. J. Glanew
ATTORNEY.

UNITED STATES PATENT OFFICE.

HAROLD ORTH, OF DENVER, COLORADO.

PICK FOR MUSICAL INSTRUMENTS.

Application filed August 13, 1919. Serial No. 317,223.

To all whom it may concern:

Be it known that I, HAROLD ORTH, a citizen of the United States, residing at Denver, in the county of Denver and State 5 of Colorado, have invented certain new and useful Improvements in Picks for Musical Instruments, of which the following is a specification.

This invention relates to picks or plectrums for use in playing stringed musical instruments, and its principal object is to provide a thimble which snugly fits the finger of the player and which has at its end a transverse lug to twang the strings of a 15 guitar, banjo, or other similar musical instrument with either a forward or back action of the finger, or both, thereby causing them to produce clear and resonant sounds similar to those produced by the steel- 20 stringed instruments of Hawaii.

Another very important object of my invention is to provide a pick of the character mentioned which strikes the strings throughout the length of its transverse lug, while 25 the hand on which it is worn occupies an easy and natural position on the instrument.

An embodiment of my improved pick has been shown in the accompanying drawings 30 in the various views of which like parts are similarly designated, and in which

Figure 1 is a perspective view of the hand of a player showing the improved pick in its operative position with relation to the strings of a musical instrument; 35

Figure 2, a perspective view of the pick drawn to an exaggerated scale;

Figure 3, a longitudinal section of the pick, and

Figure 4, an underneath end view of the same.

The pick as shown in the drawings consists of a thimble composed of two loops 5 and 6 formed integrally of a single piece of 45 metal and disposed transversely with relation to each other.

Both loops are open for their adjustment to fit fingers of different shapes and sizes, it being understood that the metal of which 50 the pick is made has sufficient inherent pliability to permit of its being bent to any desired shape.

The loops are designed to respectively encircle the fore-part of a finger and embrace the tip thereof, longitudinally of the same it being essential that they be formed

to fit snugly around the parts of the finger they engage so as to prevent deflection or lost motion while in use. The longitudinal loop which constitutes the body portion of 60 the thimble fits the end of the finger and also the inner and outer sides thereof and extends along the latter, one of the sides of the loop being longer than the other.

The U-shaped loop 6 which embraces the 65 tip of the finger is connected with the longer side of the longitudinal loop and has at its vertex, an integral lug 7 to engage the strings 8 of the instrument when they are played by the finger on which the pick is 70 worn.

The lug extends obliquely across the loop so that when the hand of the player is held in the proper position on the sound board of the instrument as shown in Figure 75 1, the lug extends in parallel relation to the strings thereof.

The oblique position of the lug on the thimble is of paramount importance in the use of my invention inasmuch as it permits 80 of striking the strings with the lug along its entire length without turning the hand from its natural position.

The engagement of the strings by the lug in this manner, prevents its slipping off the 85 strings before a full tone is gained; it insures the production of a clear and resonant sound without any special effort on the part of the player and permits of playing the instrument accurately with any required 90 rapidity and without slips or misses.

The snug fit of the loop on which the lug is formed, upon the tip of the finger, prevents deflection and lost motion and thereby aids in the production of tones of the desired 95 clearness and resonance.

In using the pick the thimble is placed on the finger with the free end of the tip-embracing loop resting upon the nail thereof so that the pressure exerted on the finger 100 in playing, is directed against the part by which the two loops of the thimble are connected and the strings can be struck with any desired force without bending the loops.

Having thus described my invention what 105 I claim and desire to secure by Letters-Patent is:

1. A pick of the class described comprising a loop adapted to encircle the fore-part of a finger, an integral substantially U-shaped loop of appreciable width extending transversely thereof and engaging both

the front and rear of the fore-part of the finger, a picking lug carried by the said U-shaped loop and extending entirely across the same diagonally with relation to the 5 plane thereof.

2. A pick of the character described comprising a loop having arms adapted to encircle the fore-part of a finger and curved downwardly at their forward ends, an integral substantially U-shaped loop of substantial width forming an extension of the 10

said arms and extending transversely thereof, said last mentioned loop having an upwardly extending portion engaging the rear side of the finger and terminating below 15 the said first mentioned loop, and a picking lug on the U-shaped loop extending entirely across the same diagonally with relation to the plane thereof.

In testimony whereof I have affixed my 20 signature.

HAROLD ORTH.
